UNITED STATES PATENT OFFICE.

THOMAS N. GILMORE, OF CRANFORD, NEW JERSEY, ASSIGNOR TO WESTINGHOUSE, CHURCH, KERR & COMPANY, OF NEW YORK, N. Y., A CORPORATION OF NEW JERSEY.

SYSTEM AND APPARATUS FOR BLOWING OFF, WASHING, AND FILLING LOCOMOTIVE-BOILERS.

1,117,947.

Specification of Letters Patent.

Patented Nov. 17, 1914.

Application filed August 9, 1911. Serial No. 643,092.

To all whom it may concern:

Be it known that I, THOMAS N. GILMORE, a citizen of the United States, residing at Cranford, county of Union, and State of New Jersey, have invented certain new and useful Improvements in Systems and Apparatus for Blowing Off, Washing, and Filling Locomotive-Boilers, fully described and represented in the following specification 10 and the accompanying drawings, forming a part of the same.

This invention relates to a system or apparatus for blowing off, washing out and filling locomotive boilers, and the object of the invention is generally to provide round house, or locomotive house, equipment for this purpose which shall be reliable and efficient in operation, and whereby the water for refilling the locomotive boilers, or for both refilling and washing out, shall be economically heated by steam separated from the blow-off water and also by exhaust steam from any available source.

A full understanding of the invention can best be given by a detailed description of a preferred embodiment of the same, and such a description will now be given in connection with the accompanying drawings in which—

Figure 1 is a diagrammatic view illustrating an approved embodiment of the invention in a system having a single hot water storage tank from which water is drawn for both washing out and filling up. Fig. 2 is an enlarged vertical sectional view of the hot water tank shown in Fig. 1. Fig. 3 is a cross sectional view of the hot water tank taken on line 3 of Fig. 2. Fig. 4 is a cross sectional view of the blow-off tank and separator taken on line 4 of Fig. 1. Fig. 5 is a diagrammatic view similar to Fig. 1 but showing the invention as embodied in a two-tank system having a second storage tank for washing water.

Referring to the drawings, and first to Figs. 1 to 4, the water and steam blow-off from the locomotive boilers are delivered through a blow-off main 10 and through a pipe 11 into a blow-off tank and separator 12. The blow-off main extends through the round house past the engine stalls and is provided with drop pipes 13 between the engine stalls, the drop pipes being provided with check valves 14 adjacent to the main. Duplicate mains

15 and 16 are also provided extending through the round house for supplying the water for washing out and filling up, and each of these supply mains is provided with drop pipes 17 and 18 respectively between the engine stalls in the customary manner. The drop pipes 13, 17 and 18 are provided with valves 19 adjacent to their lower ends and the three pipes of each set, of which sets only one is shown in the drawing, are connected below the valves 19 to a single connecting terminal 20 from which connection may be made to the boiler of a locomotive in the stall on either side of the drop pipes for blowing off or filling up, or to which a hose pipe may be connected for washing out.

The blow-off and separating tank 12 may be of any suitable construction, but a tank such as is fully described in my application No. 645,188, filed August 21, 1911, I consider best for the purpose. This tank, as is clear from Figs. 1 and 4, consists of a conical shaped tank set vertically and having an inlet opening 21 on one side connected with the pipe 11 for admitting the blown off water and steam in a direction tangential to the side of the tank, and having a steam outlet at the top and a water discharge outlet 22 in the bottom of the tank connecting with a discharge pipe 23. The tank is also provided in its lower part with baffles 24. The water and steam entering the tank tangentially take up a swirling or rotary motion, and the water traveling in a spiral direction downward into the larger lower portion of the tank with reduced velocity, gives up the maximum quantity of steam. The steam rises to pass through the outlet at the top of the tank, and the water at the bottom of the tank having had its rotary motion stopped by the baffle plates flows quietly out through the discharge pipe 23. The pipe 23 discharges into a catch basin 25 from which the water overflows and is discharged through an overflow pipe 26. In the particular arrangement shown in Fig. 1, no use is made of the blown off water after it leaves the catch basin, and the overflow pipe 26 may, therefore, discharge directly into the sewer or be connected in other suitable manner to allow the water overflowing from the catch basin to escape. The discharge pipe

23 is carried down to near the bottom of the catch basin and the overflow pipe 26 leads from near the top of the catch basin, so that the catch basin is at all times full 5 of water forming a water seal and preventing the escape of steam from the blow-off tank. The head of water seal in the catch basin determines the maximum obtainable pressure in the system, since on an increase 10 of pressure in the system above that corresponding to the head of water seal in the catch basin, the excess pressure will be relieved by blowing out through the discharge pipe 23. Sludge and scale blown out of the 15 locomotive boilers will be carried through the blow-off tank and into the catch basin, from which it may be removed as desired through a man-hole provided at the top of the catch basin, or may be allowed to pass 20 out with the water through a drain 29 controlled by a normally closed sluice valve 27 which may be opened by a handle 28.

The steam separated from the water in the blow-off tank escapes through the opening 25 in the top of the tank and passes part by pipe 30 to a large hot water storage tank 31 and part by pipe 32 to a water heater 33. The water heater 33 may be, and for best 30 results will be, of the open type, that is, one in which the steam comes into direct contact with the water to be heated. An open water heater of any suitable form may be used. The heater is connected to supply hot water to the hot water tank 31 through a 35 pipe 34 and this connection between the heater and tank is normally open so that the water will stand at the same level in both the heater and tank, the heater being set with relation to the tank so that the intended 40 normal water line of both will be at the same level. The water is supplied to the heater through an inlet pipe 35 provided with a valve 36 which is controlled through a connecting rod 37 by a float 38 within the heater. 45 The flow of water to the heater and the supply of hot water to the storage tank is thus controlled by the height of water in the tank and heater, water being automatically supplied when the water level in the tank drops 50 and the supply being cut off when the water stands at or above the desired level in the tank. Water flowing to the heater from the cold water supply pipe 40 may be preliminarily heated by passing through a coil 41 55 in the catch basin 25 and thence through a pipe 42 to the inlet pipe 35. Connection may also be provided as shown by pipe 43, for supplying the heater with water from the cold water line 44 which is connected with 60 the supply pipe 40 to take water which has not passed through the heating coil 41. Valves 45 and 46 are provided in the pipes 42 and 43 respectively for controlling the 65 source of supply of water to the heater as desired.

In addition to steam from the separator 12, the water heater is also supplied with exhaust steam from the pumps hereinafter referred to forming part of the system and with exhaust steam from any other available source, as from the power house steam engines. Fig. 1 shows pipe 50 for supplying exhaust steam from the exhaust steam pipe 51 to the pipe 32 leading from the separator to the heater. Exhaust steam from the 70 pumps is supplied to the heater through pipe 52 leading into pipe 50. A supply of steam to the heater is thus secured at all times and especially when the pumps are working; that is, when water from the tank 80 is being used. The steam enters through an opening of ample size into the water heater where it mingles with and is condensed all or in part by the water entering the heater through inlet pipe 35. The maximum flow 85 of water into the heater should for best results be fixed at the lowest possible rate of flow which will be sufficient to take care of the requirements of the system, thereby giving the opportunity of condensing the 90 maximum amount of steam and transferring to the water the maximum number of heat units. The maximum rate of inflow of water into the heater will thus be much less than the rate of outflow from the tank 31 under 95 the maximum demand. Any steam not condensed in the heater is conducted from the heater through a pipe 53 into the hot water storage tank.

The hot water storage tank 31 is preferably a steel tank of elongated form, although a tank of other suitable form or material might be employed. The steam passing from the blow-off tank and separator 12 through the pipe 30 passes by a connection through 100 the bottom of the tank 31 and near one end thereof into a manifold 55 to which are connected a number of return pipes or coils 56 mounted below the water level in the tank and ending in vertical risers 57 the open 105 ends of which extend slightly above the normal water level in the tank near one end thereof. The steam entering the coils 56, and all or the greater part of it being condensed in the coils, will not only maintain 110 the water in the storage tank. A suitable drain connection such as the drain pipe 58 leading to discharge into the catch basin is provided for removing and disposing of water condensed in the pipe coils, the end of the drain pipe 58 extending down to near the bottom 115 of the catch basin to preserve the water seal on the system. Any steam entering the pipe coils from the separator and not condensed 120 therein will escape into the space above the water level in the tank and will be utilized to further heat the water as hereinafter explained. The steam pipe 30 extends downward to the connection with the tank 31 130

from a sufficient height so that the water condensed in the pipe coils will run out through the drain pipe 58 and will not flow back through the pipe 30 into the blow-off tank. The blow-off tank and the hot water tank 31 are, however, set relatively to each other so that the steam outlet at the top of the blow-off tank or the high point of the pipe 30 is below the level of the open ends 5 of the risers 57 of the pipe coils 56, thus providing for the overflow through the heating coils, pipe 30, blow-off tank and catch basin into the sewer of excess water which may from any cause enter the hot water tank and 10 raise the water level above the ends of the risers 57.

The pipe 53 leading from the steam space of the water heater to the hot water tank connects with the hot water tank near the 20 end in which the risers 57 of the pipe coils are located, and at or near its opposite end the tank is provided with an outlet pipe 60 fitted with a back pressure valve 61. Between the inlet of the pipe 53 and the outlet 25 pipe 60 the tank is provided along its top inside surface with a number of baffles or deflectors 62 extending down nearly to the normal high water level. Uncondensed steam entering the space above the water 30 in the tank either from the heater through pipe 53 or from the steam coils may then flow along over the surface of the water to the opposite end of the tank to escape through the outlet pipe 60 and will be retarded in its flow and deflected down into 35 more intimate contact with the surface of the water by the baffle plates 62, and considerable additional heating of the water is thus secured from steam which would otherwise not be made to give up its heat. The 40 back pressure valve 61 determines the pressure maintained on the system, and will be adjusted for maintaining a suitable low pressure, usually about one pound pressure, which will serve to prevent a too rapid escape of any uncondensed steam and also prevent the complete deflection of steam from the exhaust steam pipe 51, thus permitting steam from the pipe 51 to be used for other 45 heating purposes if desired. A drain pipe 63 leading to the catch basin is provided for draining out the tank 31, this pipe being provided with a valve 64 which is normally kept closed.

50 The connections between the separator and the hot water storage tank and the water heater not only provide for the heating of the water in the storage tank for maintaining or increasing its temperature by steam passing from the separator into the heating coils 56 and by steam passing over the top 55 of the water in the tank, but under certain conditions steam entering the tank through the inlet from the pipe 53 will pass into the 60 risers 57 and heating coils 56 to be con-

densed in the coils. Such reverse flow of steam in the heating coils occurs when uncondensed steam passes from the water heater through the pipe 53 into the storage tank at a time when a boiler is not being 70 blown off. Ordinarily the greatest amount of steam supplied to the heater during times when no boiler is being blown off is supplied when water is being pumped from the storage tank for filling or washing and the 75 exhaust from the pumps is entering the heater; also if the tank and heater are full of water to their normal water level, so that no water is flowing into the heater, then substantially all the steam entering the 80 heater will pass on into the storage tank. Suppose for example, that the storage tank and heater are full of water to their normal water level, that no boiler is being blown off and that no water is being pumped from the 85 storage tank, no water will be flowing into the heater and exhaust steam entering the heater will pass through pipe 53 into the storage tank and more or less of this steam will enter the open risers of the heating coils 90 56 to be condensed in the coils and give up its heat to the water in the tank. The lower the temperature of the water in the tank, the more rapid will be the condensation of steam in the coils, and, therefore, the more steam 95 will enter the coils from the steam space in the upper part of the tank. If water is being pumped from the tank, the lowering of the water level will cause the water supply valve to the heater to be opened and 100 the inflowing water will condense steam in the heater and be heated thereby, but then also the supply of steam to the heater will be increased by the exhaust from the pump or pumps so that there will usually be at 105 such time also steam passing from the heater into the upper part of the storage tank, and the heating of the water in the tank by steam entering the coils through the risers may then continue. Exhaust steam supplied to 110 the water heater, whether from the pumps or from other sources, will thus be utilized to the best advantage not only for heating water entering the heater but also for heating the water in the storage tank. When a 115 boiler is being blown off, the supply of steam to the water heater and from the water heater to the steam space in the storage tank will be augmented by steam from the separator 12, and at the same time steam from the separator will enter the heating coils in the storage tank. The amount of steam entering the heating coils at such time will usually be such that more or less uncondensed steam will escape from the 120 heating coils into the steam space of the storage tank. It will be noticed that with the steam connections provided in the embodiment of my system as shown herein, the steam, whether from the separator or 125 130

from the pumps or from the exhaust steam pipe 51, will give up its heat to water where most needed. If, for example, a boiler is blown off at a time when the temperature 5 of the water in the storage tank is comparatively low and the tank is full, a greater proportionate part of the steam from the separator will, because of the greater condensation in the heating coils 56, be drawn 10 into the coils than if the temperature of the water in the tank were higher or if water were flowing into the heater.

Hot water is supplied to the distributing main 15 from the storage tank 31 by means 15 of a pump 70 which may be a suitable steam pump or other suitable pump and which is connected with the storage tank by a suction pipe 71 and with the distributing main 15 by discharge pipe 72. This pump is also 20 connected on its suction side by a pipe 73 with the cold water line 44, and the pipes 71 and 73 are provided with valves as shown so that the pump may be connected to supply either hot or cold water to the distributing 25 main 15. The distributing main 16 is similarly supplied by a steam pump 75 through a discharge pipe 76 and this pump is connected by suction pipe 77 with the storage tank 71 for supplying hot water to the main 16 and is also connected by pipe 78 30 with the pipe 73 and cold water main 44 for supplying cold water to the main 16, the suction pipes 77 and 78 being provided with suitable valves as shown, so that the pump 35 may be connected on its suction side to supply either hot or cold water. Either pump may thus be made to deliver either hot or cold water, and either hot or cold water may thus be supplied to either of the distributing 40 mains 15 and 16. In ordinary use of the apparatus, one of the distributing mains may be supplied with hot water from the tank 31 and the other with cold water so that by suitable adjustment of the valves 45 19 of the drop pipes 17 and 18 leading from these mains water at the proper temperature for washing out locomotive boilers may be supplied through any terminal 20, and by closing the valve 19 in the drop pipe supplying cold water and opening the valve of the drop pipe supplying the hot water, hot water at the temperature of the water in the storage tank may be supplied for filling up. The arrangement also admits, in case of 50 either pump being shut down, of supplying hot water through the distributing main supplied by the other pump, and, also, in case of necessity or if desired for any reason, cold water may be supplied through 55 either or both of the distributing mains, or warm water may be supplied.

The distributing mains 15 and 16 may be provided in the usual manner with return connections as shown to a return pipe 80 for 60 maintaining constant circulation through

the mains, the pumps being provided in the usual manner with automatic governors of suitable construction. The return pipe may be connected as shown by pipe 81 to deliver into the water heater through the supply 70 pipe 35.

Under some conditions, as where the cost of water is to be considered or where sufficient exhaust steam is not available to supplement steam blown from the locomotive 75 boilers for heating water to be used for washing out as well as water for filling up, it is desirable to retain the hot blown off water from the locomotive boilers to be used for washing out. Fig. 5 shows an embodiment of the invention in a system having an additional storage tank in which the blow-off water is stored and from which it is pumped to be used for washing out the locomotive 80 boilers. This two-tank system as 85 shown in Fig. 5 is substantially the same as the single tank system shown in Fig. 1 except for the addition of the second storage tank for the blow off water and the arrangement of the pumps. As shown in this figure, 90 hot water is supplied to the main 15, which in the ordinary intended operation of this two-tank system is the filling main, from the storage tank 31 by the steam pump 70 connected as in Fig. 1 with the tank by a suction pipe 71 and with the filling main by discharge pipe 72, and also connected on its 95 suction side by a branch from pipe 73 with the cold water line 44, the suction pipe 71 and branch from the pipe 73 being provided with valves so that the pump may be connected to supply either hot or cold water to the filling main 15. The main 15 is provided as before with a return connection through pipe 80 connected by pipe 81 to the 100 heater supply pipe 35 for maintaining constant circulation through the filling main, the pump being provided with an automatic 105 governor.

The overflow pipe 26 from the catch basin 110 25, instead of connecting to the sewer, discharges into a masonry or other tank or hot well 85 in which the blown off water is collected and stored to be used as wash water. This tank is provided with an overflow pipe 86 which connects with a pipe 87 leading to the sewer or otherwise connected to allow the overflow water to escape. The overflow pipe 86 leads from a chamber 88 partitioned off at one end of the tank and communicating with the main portion of the tank below the normal water level only through a hole 89 at and near the bottom of the partition. The overflow water will thus ordinarily be drawn from the bottom of the tank where the water is coldest. The bottom of the overflow chamber 88 of the tank is depressed or recessed as shown at 90 to provide a pocket into which sludge, scale or other matter carried by the water may settle and from which 115 120 125 130

they may be removed through a man-hole 91 or be allowed to pass off with the water through a drain pipe 92 leading to the sewer pipe 87, the outlet to the pipe 92 being controlled by a normally closed sluice valve 93 which may be opened by means of a handle 94. The pipe 87 also connects with the outlet from the bottom of the catch basin 25. The overflow pipe 26 is also connected with 10 the sewer pipe 87 by means of a by-pass pipe 95 so that by means of the valves 96 and 97 provided respectively in the pipe 95 and in the pipe 26 beyond its connection with the pipe 95 the overflow may be directed either 15 to the hot well or directly to the sewer as desired.

Water from the hot well or washing water storage tank 85 is delivered to the main 16, which in the ordinary use of this two-tank 20 system is the wash water main, by means of a pump 100 which is connected with the storage tank by a suction pipe 101 and with the main 16 by a discharge pipe 102. The suction pipe 101 takes its water from the 25 tank through a hinged extension 103, the inner end of which is supported by a float 104 so that it will take water from near the top where the temperature of the water is highest and where the water is free from 30 scale, sludge or other suspended matter. The pump 100 is also connected on its suction side to the pipe 73 leading from the cold water main 44. The suction pipe 101 and the connection from the pipe 73 are 35 provided with valves as shown, so that the pump may be made to deliver hot or warm water from the storage tank 85 or cold water from the main 44 to the wash water main 16. For maintaining circulation in the main 40 16, the main is provided with a return connection such as the return pipe 105 leading from the end of the main to the blow-off main 10, and the pump is provided with the usual automatic governor of any suitable 45 construction.

It will be seen that with the valves controlling the suction of the pump 70 set to cause the pump to supply hot fresh water from the tank 31 to the filling line 15, and 50 with the valves controlling the suction of the pump 100 set for causing said pump to supply water from the tank 85 to the washing line 16, water for either filling or washing will at all times be available at any of 55 the terminals 20 in the round house, it being only necessary when the connection is made from any terminal 20, either to a locomotive boiler for filling, or to the wash out hose for washing out, to open the valve 19 in the 60 drop pipe 17 or the drop pipe 18 as the case may be. By setting the valves controlling the suction of the pump 100 to cause cold water to be supplied by this pump to the distributing line 16, the system as shown in 65 this figure may be used in the manner de-

scribed for the single tank system of Fig. 1, that is, with one distributing line supplied with hot water from the tank 31 and the other with cold water; and in order that either pump may be made to deliver through 70 its distributing main either fresh hot water from the tank 31 or cold water, the pump 100 is connected with the tank 31 by a suction pipe 106 provided with a valve 107.

The operation and use of the system, 75 either with the single tank of Fig. 1 or with the two-tank arrangement of Fig. 5, will be understood from the foregoing description. The system, including the introduction of steam coils into the hot water storage tank 80 and the manner of connecting up the steam supply to these coils, together with the means or connections provided for introducing uncondensed steam from the water heater into the top of the storage tank and 85 for causing said steam to pass over and in contact with the water in the tank and into the steam coils or heating pipes, provides a most efficient means of utilizing steam separated from the contents blown from locomotive boilers and exhaust steam from the pumps and other available sources for maintaining and raising the temperature of the water in the hot water storage tank; and the restricting of the inflow of fresh water 90 to the water heater as described, affords the best conditions for condensing the steam admitted to the heater and transferring its heat units to the water so as to obtain the most efficient heating of the water and the 95 supply of water at the maximum temperature to the hot water storage tank.

What is claimed is:—

1. In a boiler blow-off, washing and filling system, the combination of a separator, a 105 blow-off pipe leading to the separator, a storage tank, means for heating water on its way to the storage tank by blow-off water from the separator, means for further heating the water before it enters the storage 110 tank by steam from the separator, and means for further heating the water in the storage tank by steam coming direct from the separator.

2. In a boiler blow-off, washing and filling 115 system, the combination of a separator, a blow-off pipe leading to the separator, a storage tank, means for heating water on its way to the storage tank by blow-off water from the separator, a water heater for further heating the water before it enters the storage tank by exhaust steam and by steam from the separator, and a separate steam connection from the water heater to the storage tank for the passage of uncondensed 120 steam from the water heater to further heat the water in the storage tank.

3. In a boiler blow-off, washing and filling system, the combination of a separator, a 130 blow-off pipe leading to the separator, a

storage tank, means for heating water on its way to the storage tank by blow-off water from the separator, a water heater for further heating the water before it enters the storage tank by exhaust steam and by steam from the separator, a separate steam connection from the water heater to the storage tank for the passage of uncondensed steam from the water heater to further heat the water in the storage tank, and means for heating the water in the storage tank by steam coming direct from the separator.

4. In a boiler blow-off, washing and filling system, the combination of a separator, a blow-off pipe leading to the separator, a storage tank, a water heater in which water is heated on its way to the storage tank, a connection for supplying steam from the separator to said water heater, heating means for further heating the water in the storage tank, and a connection for supplying steam from the separator to said heating means.

5. In a boiler blow-off, washing and filling system, the combination of a separator, a blow-off pipe leading to the separator, a storage tank, an open water heater in which water flowing to the storage tank is heated by steam from the separator, means for controlling the supply of water according to the level of water in the storage tank, and a separate steam connection from the heater to the storage tank for the passage of uncondensed steam from the heater to further heat the water in the tank.

6. In a boiler blow-off, washing and filling system, the combination of a separator, a blow-off pipe leading to the separator, a storage tank, a steam pump for delivering water from the storage tank, a water heater for heating water flowing to the storage tank, said heater being supplied with exhaust steam from the pump, means for controlling the supply of water according to the level of water in the storage tank, and means for heating the water in the storage tank by steam direct from the separator.

7. In a boiler blow-off, washing and filling system, the combination of a separator, a blow-off pipe leading to the separator, a storage tank, an open water heater for heating water flowing to the storage tank, said heater being supplied with steam from the separator and also with exhaust steam, means for preliminarily heating the water flowing to the heater by blow-off water from the separator, and means for maintaining the temperature of the water in the storage tank by steam from the heater and also by steam direct from the separator.

8. In a boiler blow-off, washing and filling system, the combination of a separator, a blow-off pipe leading to the separator, a storage tank, a water heater for heating water flowing to the storage tank by ex-

haust steam, means for controlling the supply of water according to the level of water in the storage tank, a connection for supplying uncondensed steam from the water heater to heat the water in the storage tank, and means for heating water in the storage tank by steam from the separator.

9. In a boiler blow-off, washing and filling system, the combination of a separator, a blow-off pipe leading to the separator, a storage tank, a water heater for heating water flowing to the storage tank, a valve for controlling the supply of water to the heater controlled by the level of water in the heater, a connecting passage between the heater and the storage tank below the water level, the heater and storage tank being set relatively to each other so that the intended normal water level of both shall be the same, a steam passage leading from the separator to the heater, and a steam passage leading from the separator to the storage tank.

10. In a boiler blow-off, washing and filling system, the combination of a separator, a blow-off pipe leading to the separator, a storage tank, a water heater for heating water flowing to the storage tank, a valve for controlling the supply of water to the heater controlled by the level of water in the heater, a connecting passage between the heater and storage tank below the water level, the heater and the storage tank being set relatively to each other so that the intended normal water level of both shall be the same, means for supplying steam to the heater from a source other than the separator, means for heating water in the storage tank by steam from the separator, and a passage leading from the heater for supplying uncondensed steam from the heater for heating water in the storage tank.

11. In a boiler filling system, the combination with a storage tank, of a water heater for heating water flowing to the tank, a connecting passage between the heater and the tank below the water level, a passage connecting the steam space of the heater and the steam space of the tank, and a valve for controlling the supply of water to the heater controlled by the water level in the heater.

12. In a boiler blow-off, washing and filling system, the combination of a separator, a blow-off pipe leading to the separator, a storage tank, means for heating water flowing to the storage tank, means for supplying steam to the water-heating means, a heating pipe mounted in the storage tank connected to receive steam from the separator and open to the interior of the tank above the water level, and means providing a passage connecting the steam space in the water-heating means with the storage tank.

13. In a boiler blow-off, washing and fill-

- ing system, the combination of a separator, a blow-off pipe leading to the separator, a storage tank, a heating pipe in the storage tank connected to receive steam from the 5 separator and open to the interior of the tank above the water level, and means for supplying steam from a source other than the separator to the space in the storage tank above the water level.
- 10 14. In a boiler blow-off, washing and filling system, the combination of a separator, a blow-off pipe leading to the separator, a storage tank, a heating pipe in the storage tank connected to receive steam from the 15 separator, and means for supplying steam at low pressure from a source other than the separator to flow through said heating pipe in the reverse direction from that in which the steam from the separator flows 20 therethrough.
- 15 15. In a boiler blow-off, washing and filling system, the combination of a separator, a blow-off pipe leading to the separator, a storage tank, a heating pipe in the storage 25 tank connected to receive steam from the separator, and a connection for supplying a relatively small amount of steam from a source other than the separator to enter said heating pipe when a boiler is not being 30 blown off.
16. In a boiler blow-off, washing and filling system, the combination of a separator, a blow-off pipe leading to the separator, a storage tank, a heating pipe in the storage 35 tank connected at one end to receive steam from the separator, and a connection for supplying steam at low pressure and in relatively small amount to the other end of said heating pipe from a source of substantially 40 continuous supply.
17. In a boiler blow-off, washing and filling system, the combination of a separator, a blow-off pipe leading to the separator, a storage tank, a water heater for heating by 45 steam water flowing to the storage tank, a connection for supplying to the heater steam from a source other than the separator, a connection for the passage of uncondensed steam from the heater to the tank, and a 50 heating pipe in the storage tank connected to receive steam from the separator and open to the interior of the tank above the water level.
18. In a boiler blow-off, washing and filling system, the combination of a separator, a blow-off pipe leading to the separator, a storage tank, a water heater for heating water flowing to the storage tank, means for 55 controlling the supply of water according to the amount of water in the tank, a connection for supplying steam to the heater from a source other than the separator, a connection for the passage of uncondensed steam from the heater to the storage tank, and a 60 heating pipe in the storage tank connected 65 to receive steam from the separator and open to the interior of the tank above the water level.
19. In a boiler blow-off, washing and filling system, the combination of a separator, a blow-off pipe leading to the separator, a storage tank, a heating pipe in the storage tank connected to receive steam from the separator and open to the interior of the tank above the water level, a steam pump for 70 pumping water from the storage tank, means for supplying water to the tank, and means for supplying exhaust steam from the pump to the space in the tank above the water level.
20. In a boiler blow-off, washing and filling system, the combination of a separator, a blow-off pipe leading to the separator, means for providing a water seal past which the blow-off water flows from the separator, 75 a storage tank, a water heater for heating water supplied to the storage tank, a connection for supplying steam from an exhaust steam line to the water heater, a connection for the passage of uncondensed steam from 80 the heater into the storage tank, an outlet from the system provided with a low pressure back-pressure valve, and means for heating the water in the storage tank by steam from the separator.
21. In a boiler blow-off, washing and filling system, the combination of a separator, a blow-off pipe leading to the separator, a storage tank, a water heater for heating water supplied to the storage tank by exhaust steam and by steam from the separator, a connection for the passage of uncondensed steam from the heater into one end 85 of the storage tank, a heating pipe in the storage tank connected to receive steam from the separator and opening into the tank at the end of the tank at which the uncondensed steam from the heater is received, and an outlet at the opposite end of the tank provided with a back pressure valve.
22. In a boiler blow-off, washing and filling system, the combination of a separator, a blow-off pipe leading to the separator, a storage tank, and heating pipes mounted within the tank below the water level and connected at one end to receive steam from the separator and having at the other end openings to the interior of the tank slightly above the normal water level, said heating 90 pipes being connected to provide an overflow passage from the tank past a pressure-maintaining water seal.
23. In an apparatus for supplying hot water, the combination of a storage tank, a water heater for heating by steam water flowing to the storage tank, means for controlling the supply of water according to the amount of water in the storage tank, a heating pipe within the storage tank, and a connection for supplying uncondensed steam 100

from the heater to said heating pipe in the storage tank.

24. In an apparatus for supplying hot water, the combination of a storage tank 5 having a heating pipe therein connected with an intermittent steam supply and open to the interior of the tank above the water level, a steam pump for pumping water from the tank, and means for supplying 10 exhaust steam from the pump to the interior of the tank above the water level.

25. In an apparatus for supplying hot water, the combination of a storage tank having a heating pipe mounted therein connected with an intermittent steam supply 15 and open to the interior of the tank above the water level, a water heater for heating water flowing to the tank, a steam pump for pumping water from the tank, connections for supplying exhaust steam from the pump to the heater, and a connection for the passage of uncondensed steam from the heater to the tank.

26. In an apparatus for supplying hot water, the combination with a storage tank, 25 of a heater for heating water flowing to the tank, means for supplying steam to the heater, a connection for the passage of uncondensed steam from the heater to the 30 space above the water level in the tank, and a heating pipe mounted within the tank and open to the space above the water level in the tank and provided with a connection for carrying off water of condensation 35 formed therein.

27. In an apparatus for supplying hot water, the combination with a storage tank, of a water heater for heating water flowing to the tank, means for controlling the 40 supply of water to the heater according to the amount of water in the tank, means for supplying steam to the heater, a connection for the passage of uncondensed steam from the heater to the tank, a back pressure valve 45 connected to control the pressure in the tank, and a heating pipe mounted in the tank and open to the interior of the tank above the normal water level and connected to receive steam from an intermittent steam 50 supply.

28. In an apparatus for supplying hot water, the combination of a storage tank having a heating pipe mounted therein connected with an intermittent steam supply, 55 a water heater for heating water flowing to the tank, means for controlling the supply of water according to the level of water in the tank, means for supplying steam to the water heater from a source other than the 60 source of supply to the heating pipe, and a connection for the passage of uncondensed steam from the heater to said heating pipe.

29. In an apparatus for supplying hot water, the combination of a storage tank, a 65 heating pipe mounted within the tank and

connected with an intermittent steam supply, a water heater for heating water flowing to the tank, means for controlling the supply of water according to the level of water in the tank, means for supplying exhaust steam to the water heater, a connection for the passage of uncondensed steam from the heater to said heating pipe, and a back pressure valve connected to limit the 70 pressure in the heating pipe. 75

30. In an apparatus for supplying hot water, the combination of a storage tank, a heating pipe in the storage tank connected at one end with an intermittent steam supply, and a connection for supplying steam 80 at low pressure and in relatively small amount to the other end of said heating pipe from a source of substantially continuous supply.

31. In a boiler blow-off, washing and filling system, the combination of a separator, a blow-off pipe leading to the separator, a water heater, means for supplying steam to the water heater, means for supplying fresh water to the water heater, a storage 90 tank 31 to which water is supplied from the water heater, said tank being of horizontally elongated form and being provided with heating pipes 56 connected to receive steam from the separator and open to the 95 interior of the tank above the water level near one end of the tank, a connection for supplying uncondensed steam from the heater to the space above the water level in the tank adjacent to the ends of the pipes 100 56, and a steam outlet at the opposite end of the tank.

32. In a boiler blow-off, washing and filling system, the combination of a separator, a blow-off pipe leading to the separator, 105 means providing a water seal past which the blow-off water flows from the separator, a storage tank, a water heater for heating water supplied to the storage tank, a connection for the passage of uncondensed steam 110 from the heater to the storage tank, heating pipes in the storage tank connected to receive steam from the separator and opening to the interior of the tank, and an outlet from the system provided with a back pressure valve. 115

33. In a boiler blow-off, washing and filling system, the combination of a separator, a blow-off pipe leading to the separator, 120 means providing a water seal past which the blow-off water flows from the separator, a storage tank, a water heater for heating water supplied to the storage tank, means to supply steam to the heater from a source other than the separator, a connection for 125 the passage of uncondensed steam from the heater to the storage tank, heating pipes in the storage tank connected to receive steam from the separator and opening to the interior of the tank above the normal water 130

level, and an outlet from the system provided with a back pressure valve.

34. In a boiler blow-off, washing and filling system, the combination of a separator, 5 a blow-off pipe leading to the separator, means providing a water seal past which the blow-off water flows from the separator, a storage tank, a steam pump for delivering water from the storage tank, a water heater 10 for heating water supplied to the storage tank by exhaust steam from the pump, a connection for the passage of uncondensed steam from the heater to the storage tank, heating pipes in the storage tank connected 15 to receive steam from the separator and opening to the interior of the tank above the normal water level, and an outlet from the system provided with a back pressure valve.

35. In a boiler blow-off, washing and filling system, the combination of a separator, 20 a blow-off pipe leading to the separator, means providing a water seal past which the blow-off water flows from the separator, a storage tank, a water heater for heating 25 water supplied to the storage tank, means to supply steam to the heater from a source other than the separator, a heating pipe in the storage tank connected to receive steam from the separator, a connection for the 30 storage of uncondensed steam from the heater to said heating pipe, and an outlet from the system provided with a back pressure valve.

36. In a boiler blow-off, washing and filling system, the combination of a separator, 35 a blow-off pipe leading to the separator, means providing a water seal past which the blow-off water flows from the separator, a storage tank, a steam pump for delivering 40 water from the storage tank, a water heater for heating water supplied to the storage tank by exhaust steam from the pump and by steam from another source other than the separator, a heating pipe in the storage 45 tank connected to receive steam from the separator, a connection for the passage of uncondensed steam from the heater to said heating pipe, and an outlet from the system provided with a back pressure valve.

50 37. In a boiler blow-off, washing and filling system, the combination of a separator, a blow-off pipe leading to the separator, a discharge pipe leading from the separator for discharging the blow-off water, means 55 for providing a water seal to prevent the escape of steam from the separator through the water discharge pipe and to limit the maximum pressure in the system, a hot water storage tank, a heating pipe within 60 the storage tank connected to receive steam from the separator and open to the interior of the tank above the water level, and a drain pipe for the water of condensation from the heating pipe provided with a water 65 seal, said heating pipe and the steam con-

nexion thereto being arranged so that excess water in the storage tank will over-flow through the heating pipe and said connection and through the separator and the discharge pipe leading from the separator.

70

38. In a boiler blow-off, washing and filling system, the combination of a separator, a blow-off pipe leading to the separator, a storage tank for washing water supplied with blow-off water from the separator, a 75 storage tank for filling water, means for supplying fresh water to the filling water tank, means for heating the filling water by the blow-off water, and means for further heating the filling water by steam from the 80 separator.

39. In a boiler blow-off, washing and filling system, the combination of a separator, a blow-off pipe leading to the separator, a storage tank for washing water, a storage 85 tank for filling water, a receptacle into which the blow-off water is discharged from the separator, an overflow connection leading from said receptacle to the washing water tank, a heating coil mounted in said receptacle for preliminarily heating water supplied to the filling water tank, and means for further heating the filling water by steam from the separator.

90

40. In a boiler blow-off, washing and filling system, the combination of a separator, a blow-off pipe leading to the separator, a storage tank for filling water, means for heating the water supplied to the filling water tank by exhaust steam, means for heating the filling water by steam from the separator, a storage tank for washing water supplied with blow-off water from the separator, and means for preliminarily heating the filling water by the transfer thereto of 100 heat from the blow-off water.

95

41. In a boiler blow-off, washing and filling system, the combination of a tank for filling water, a tank for washing water, means for supplying fresh water to the filling water tank, means for heating the filling water by the blown off boiler contents, means for supplying the washing water tank with blow-off water, a distributing line for filling water, a distributing line for 110 washing water, a pump for supplying the filling water line connected on its suction side to supply hot water from the filling water tank or cold water from a cold water supply, a pump for supplying water to the 115 washing water line connected on its suction side to supply water from the washing water tank or cold water from the cold water supply.

105

42. In a boiler blow-off, washing and filling system, the combination of a separator, a blow-off pipe leading to the separator, a storage tank for washing water connected to receive the blow-off water from the separator, a storage tank for filling water, means 120

125

130

for supplying fresh water to the filling water tank, means for heating the filling water by steam from the separator, a distributing line for filling water, a distributing line for 5 washing water, a pump for supplying water to the filling water line connected on its suction side to supply hot water from the filling water tank or cold water from a cold water supply, a pump for supplying water 10 to the washing water line connected on its suction side to supply water from the wash-

ing water tank or water from the filling water tank or cold water from a cold water supply.

In testimony whereof, I have hereunto set 15 my hand, in the presence of two subscribing witnesses.

THOMAS N. GILMORE.
